UNITED STATES PATENT OFFICE

2,585,623

SCISSOR SHARPENER

Jacob Brockley, Newport News, Va.

Application October 5, 1950, Serial No. 188,584

1 Claim. (Cl. 51—156)

1

This invention relates to a scissor sharpener and is an improvement over the construction embodied in my copending application Serial No. 57,247, filed October 29, 1948, now abandoned, for Scissor Sharpener.

An object of this invention is to provide a scissor sharpener which embodies a frame having an abrading wheel mounted thereon with a ledge or shelf for supporting a scissor blade whereby the blade may be drawn laterally across the wheel.

Another object of this invention is to provide an improved securing pin for the abrading wheel which will facilitate assembly, and reduce production costs.

With the above and other objects in view, my invention consists in the arrangement, combination and details of construction disclosed in the drawings and specification, and then more particularly pointed out in the appended claim.

In the drawings:

Figure 1 is a detail front elevation of a scissor sharpener constructed according to an embodiment of this invention.

Figure 2 is a sectional view taken on the line 2—2 of Figure 1.

Figure 3 is a top plan view of the device.

Figure 4 is a fragmentary sectional view taken on line 4—4 of Figure 2.

Referring to the drawing the numeral 10 designates generally a frame structure embodying an upright plate 11 which is braced by means of a right angularly disposed bracing web 12. The plate 11 has extending downwardly therefrom a T-shaped shank 13 and the shank 13 terminates at its lower end in a laterally projecting boss 14 through which a clamping screw 15 threadably engages. A fixed clamping jaw or plate 16 extends right angularly from the lower end of the vertical plate 11, and a pair of vertical flanges 17 extend from the plate 11 and also from the jaw or plate 16.

A pair of horizontally disposed ledges or shelf members 18 extend outwardly from the flanges 17 and provide a supporting means for supporting the flat inner side of a scissor blade when the blade is being sharpened. An abrading wheel 19 is secured to the upper end of the frame 10 and the latter is formed with a boss 20 having an opening 21. A headed wheel securing pin 22 extends through the center of the abrading wheel 19 and is pressed into the opening 21.

A spider shaped resilient washer 23 is interposed between the head of the pin 22 and the adjacent side of the wheel 19. Preferably a

2

washer 24 is interposed between the radial and resilient arms 25 of the resilient washer 23 and the inner side of wheel 19. A washer 26 is also interposed between the rear side of the abrading wheel 19 and the forward side of the plate 11. The resilient washer 23 provides a means whereby the abrading wheel will normally and resiliently be held against rotation, but may be forcibly rotated so as to present to the blade a clean and unridged or grooved peripheral surface. The flanges 17 with the plate or jaw member 16 provide a pocket or receptacle 27 wherein the grindings are adapted to be caught.

The two washers 24 and 26 provide a means whereby the wheel 19 may be held under constant pressure from resilient washer 23 and wheel 19 may be manually turned without cutting the arms 25 of washer 23.

In the use of this device the frame 10 is clamped to an edge of a support by means of a clamping screw 15 and the jaw 16. The two blades of the scissors are opened, and one blade is laid flat on the ledge or supporting member 18 with the cutting edge of the blade confronting the periphery of the abrading wheel 19. The cutting edge of the blade is then pressed against the wheel 19 and drawn across the wheel from one end of the blade to the other. This operation is repeated until a relatively keen edge is formed on the scissor blades.

By providing a sharpener as hereinbefore described and particularly the improved abrading wheel supporting pin the assembly of the device is greatly facilitated as the pin 22 is secured in the boss 20 by means of a press fit. This securing of the pin 22 is such as to place the resilient washer or spider 23 under sufficient tension to frictionally hold the abrading wheel 19 against free rotation.

In order to prevent the formation of transverse grooves in the wheel face, which might result from repeated engagement of a scissor blade with the wheel held in one position, and to preserve a smooth ungrooved wheel face, the wheel may be partially turned during the sharpening operation.

I do not mean to confine myself to the exact details of construction herein disclosed but claim all variations falling within the purview of the appended claim.

What is claimed is:

A scissor blade sharpener, comprising a base having a horizontally disposed fixed member of substantially rectangular form, clamp means independently carried by said base, an upright mem-

ber having a bore therein disposed at one side of said base, said upright having oppositely disposed side extensions attached to one side of said base, a pair of spaced vertical walls affixed to said base and disposed at right angles to said side extensions to form an open-top receptacle extending at right angles to said upright, said vertical side walls having their top edges formed as oppositely extending right angularly disposed flanges lying in the same horizontal plane, a transverse support member having a head force fitted in said bore of said upright in overhanging relation to said receptacle, an abrasive wheel having a recess in one face thereof rotatably carried by said support and extending into said receptacle between said spaced flanges for engagement by a scissor blade supported by either one of said flanges to engage said wheel at a fixed angle, said flanges being equidistant from the periphery of said wheel, a spacing disc disposed between said wheel and said upright, a friction plate engaging the opposite side of said wheel in said recess, and a spider-like spring means carried by said support member and wholly contained within said recess for spring engagement between said head and said fric-

tion plate to frictionally restrain said wheel against free rotation.
